APPARATUS FOR PRODUCING ADDITIONAL DRAFT IN DRAWING FRAMES

Jan Weinberger, Chrastava, Czechoslovakia, assignor of twenty-five per cent to St. George Textile Corporation, New York, N. Y., a corporation of New York

Application October 25, 1937, Serial No. 170,912
In Yugoslavia October 27, 1936

4 Claims. (Cl. 19—159)

This invention concerns an apparatus for producing additional draft in drawing frames and consists in the arrangement that the slivers leaving the drawing frame on their way to the known rotary cans are subjected to an additional draft in order to exclude any harmful effects on the sliver arising during its being deposited in the rotary cans, and also the better to prepare such sliver for treatment in the subsequent frame as well as overcoming atmospheric and static conditions.

The foregoing problem set up as the basis of this invention has been solved constructively in the manner that the sliver delivered from the known drawing frame is carried through a special drawing field which is formed between the pair of delivery rollers of the drawing frame and the pair of drawing rollers lying within reach of the upper plate of the sliver can. By an appropriate selection of the surface speed of the pair of drawing rollers this drawing field may be adjusted in agreement with the material worked for various effects of the draft.

The drawings illustrate an apparatus constructed according to the invention, partly broken away and shown in section. Figure 1 is a top plan view of the apparatus; Figure 2 is a vertical cross-sectional view taken on line 2—2 of Fig. 1; Figure 3 is a vertical cross-sectional view taken on line 3—3 of Figure 1; and Figure 4 is a horizontal sectional view taken on line 4—4 of Fig. 3.

The upper rotary plate 12, provided with the inlet and outlet channel 10, 11, respectively, for the sliver 7, is rotatably placed in the known manner above the rotary can C and revolved by the toothed ring 13 which is engaged by a spur wheel not shown in the drawings.

Into the upper wall of the stationary case 14, surrounding the upper rotary plate 12 is to be set the toothed ring 15 that is retained therein by the screws 16. In the lower side of this case wall there is cut the groove 17 having a common axis with the upper plate.

The toothed ring 15 is engaged by the spur wheel 18 fixed on the shaft 18a which carries at its upper end the loose ring 19 guided in the groove 17. The shaft 18a carrying the spur wheel 18 is lodged rotatably in the bearing 20, rigid with the upper rotary plate 12 and carries a toothed bevel wheel 21 engaging the toothed bevel wheel 22. The shaft 18a is supported at its lower end in the bearing 20a.

The shaft 22a supporting the spur wheel 22

is lodged rotatably in the blocks 23 connected with the upper rotary plate 12 and carries one drawing roller 24 and at its end the spur wheel 25. This wheel 25 engages the spur wheel 26 seated firmly on its axle 26a which is, in the cut-outs of the block 23, projected to the influence of the springs 27. On the axis of the spur wheel 26 sits the second drawing roller 28. The drawing rollers 24, 28, are cleaned by the cleaning pads 29 which are springwise pressed against them.

As will be seen, it is possible, by an appropriate change of the gear ratio between the toothed ring 15 and the spur wheel 18, to change the surface speed of the drawing rollers and thus to produce the ever useful and desirable additional draft between the delivery rollers and the drawing rollers 24, 28.

While there is herein shown and described the preferred embodiment of the invention, it is nevertheless to be understood that minor changes may be made therein without departing from the spirit and scope of the invention as claimed.

I claim:

1. In a machine of the class described, means for feeding the sliver to a can including a rotary plate, an inclined sliver channel rising from the rotary plate, a stationary case above the plate and into which the upper end of the channel rotatably extends, said plate being rotatable on a vertical axis extending centrally through the upper end of the inclined channel whereby a sliver passing through the channel remains at all times spaced from the wall thereof, a pair of sliver drafting rollers extending across the channel adjacent the lower end thereof for lengthening the sliver and holding the same spaced from the channel walls, and a gear drive for the rollers cooperatively carried by the rotary plate and stationary case and rendered operable upon rotation of the plate.

2. In a machine of the class described, means for feeding a sliver to a can including a rotary plate, an inclined sliver channel rising from the rotary plate, a stationary case above the plate and into which the upper end of the channel rotatably extends, said plate being rotatable on a vertical axis extending centrally through the upper end of the inclined channel whereby a sliver passing through the channel remains at all times spaced from the walls thereof, a pair of sliver drafting rollers extending across the channel adjacent the lower end thereof for lengthening the sliver and holding the same spaced from the channel walls and means for operating the

drafting rollers rendered operable upon rotation of the plate.

3. In a machine of the class described, means for feeding a sliver to a can including a rotary plate, an inclined sliver channel rising from the rotary plate, a stationary case above the plate and into which the upper end of the channel rotatably extends, said plate being rotatable on a vertical axis extending centrally through the upper end of the inclined channel whereby a sliver passing through the channel remains at all times spaced from the walls thereof, a pair of sliver drafting rollers extending across the channel adjacent the lower end thereof for lengthening the sliver and holding the same spaced from the channel walls, a gear train drive for the drafting rollers cooperatively carried by the rotary plate and stationary case and rendered operable upon rotation of the plate, including a ring gear 10 on the stationary case and a pinion of the gear train carried by the rotary plate for planetarily moving around the ring gear.
4. In a machine of the class described, means for feeding a sliver to a can including a rotary

plate, an inclined sliver channel rising from the rotary plate, a stationary case above the plate and into which the upper end of the channel rotatably extends, said plate being rotatable on a vertical axis extending centrally through the upper end of the inclined channel whereby a sliver passing through the channel remains at all times spaced from the walls thereof, a pair of sliver drafting rollers extending across the channel adjacent the lower end thereof for lengthening 10 the sliver and holding the same spaced from the channel walls, a gear drive for the drafting rollers cooperatively carried by the rotary plate and stationary case and rendered operable upon rotation of the plate, including a ring gear on the stationary case, a vertical shaft on the rotary plate having a journaled bearing at its lower end in the plate, said stationary case having a downwardly opening annular groove into which the upper end of the shaft extends for guided movement therein, a gear train between the shaft and drafting rollers and a pinion on the shaft engaged with the ring gear. 15

JAN WEINBERGER.
